UNITED STATES PATENT OFFICE.

WILLIAM M. BRUCE, JR., OF SPRINGFIELD, OHIO, ASSIGNOR, BY DIRECT AND MESNE ASSIGNMENTS, TO THE SELECT TELEPHONE MANUFACTURING COMPANY, OF SPRINGFIELD, OHIO, A CORPORATION OF OHIO.

LOCK-OUT SYSTEM FOR PARTY-LINE TELEPHONES.

No. 833,298.

Specification of Letters Patent.

Patented Oct. 16, 1906.

Application filed October 23, 1905. Serial No. 283,921.

To all whom it may concern:

Be it known that I, WILLIAM M. BRUCE, Jr., a citizen of the United States, residing at Springfield, in the county of Clark and State of Ohio, have invented certain new and useful Improvements in Lock-Out Systems for Party-Line Telephones, of which the following is a specification.

My invention relates to improvements in lock-outs for party-line telephones.

The object of the invention is to provide novel means in a common-battery system whereby when one subscriber of a party-line puts the line in use by taking down his receiver the other subscribers on the line are automatically locked out.

A further object of the invention is to provide novel means by which a subscriber on a party-line may, if he desires, communicate with other subscribers on the same line or permit another subscriber on the line to come into the line in common with the first subscriber.

I attain these objects by the construction shown in the accompanying drawing, which represents a diagrammatic view showing three subscribers' stations and the subscribers' connection at the central station.

In the said drawing, *a* and *b* represent the opposite sides of the main line, to which any suitable number of subscribers' stations may be connected in the usual way. *B* represents the common battery at the central station, which is grounded on one side, as shown at *G*. The terminals of the line *a b* are connected in the usual way to a switch, preferably of the ordinary spring-jack type. I have shown the battery connected to the line through impedance-coils *a' b'*, which is the usual practice in common-battery work. These impedance-coils, while not objectionable, are not necessary to the operation of my system, my improvement being adapted to any of the common-battery systems in use, whether with or without the impedance-coils.

I have shown three stations, (marked 1, 2, and 3 in the diagrammatic view,) although, as before stated, any suitable number may be employed. From the subscribers' terminals *a² b²* of the line-wires *a b* may be traced at each subscriber's station the usual ring-

ing-circuit *d d d*, including the bell *d'* and the condenser *d²*. In this ringing-circuit I include a circuit-breaking switch *d³* for a purpose hereinafter described. From the same terminal *a² b²* may be traced the talking-circuit *e e*, &c. This talking-circuit includes a circuit-breaker *e'*, normally closed, operated by a relay *f'*, also a circuit-breaker *e²*, normally opened, operated by the ordinary receiver-hook, a circuit-breaker *e³*, operated by a push-button *d⁴*, and a circuit-breaker *e⁴*, normally open, operated by a relay *f²*. This circuit also includes the transmitter *t* and the receiver *r* in the usual way. From the terminal of the circuit-breaking switch *e³* of the talking-circuit there is a branch line *ff*, which includes a relay *f²* and is connected to ground, as shown. The relay *f'* is included in the normally closed circuit, which extends from the terminal *b²* through the circuit-breaker *e⁴* and line *gg* to ground. The terminal *b²* represents the same side of the line *a b* that is grounded at the central station, and hence no current will pass through this relay under ordinary conditions, as both ends of the wire are grounded on the same side of the battery *B*.

From a point preferably between the condenser *d²* and bell *d'* I extend a branch line *h* to a circuit-closing switch *h'*, also adapted to be operated by the push-button *d⁴* for a purpose hereinafter specified.

As thus described the operation of the device is as follows: The relay *f'*, being in a normally grounded circuit and without current, allows the circuit-breaker *e'* to remain normally closed in the talking-circuit *e*, which is, however, open at the switch *e²*, operated by the telephone-hook. This talking-circuit *e* is also broken at the circuit-breaker *e⁴*, so that these instruments are not bridged across the line, and no current flows from one side of the line to the other until the switches *e²* and *e⁴* are both operated. The relay *f'*, being in the grounded circuit and on the same side of the line as *e* and there being no current flowing from one side of the line to the other, will not be operated. As soon as a bridge is established across the main line-wires *a b*, however, the current flowing through this bridge will escape at all the legs or branches which are attached to the line *b*.

This bridge is established at any subscriber's station when the receiver is taken off the hook. The connection is first formed at e^3 , which establishes a circuit from line a through the branch e and the relay f^2 to ground. This operates the relay f^2 and closes the switch e^4 , thus completing the bridge across the line. The operation of the switch e^4 also breaks the circuit through the relay f' at the 5 subscriber's station which has thus been operated and prevents the relay f' from operating. In every other subscriber's station, however, the bridge having been thus established across the line, the current flows from 10 the line-wire a through the subscriber's talking-circuit (whose telephone has been removed from the hook) to line-wire b , and thence from line-wire b to the other subscribers' stations and to ground through the relay f' . 15 The relays f' are thus operated and the subscriber's talking-circuit at every other station except the one first operated is broken and remains broken so long as current is flowing from one side of the line to the other 20 through the bridge thus established.

Should a subscriber desire to communicate with another subscriber on the same line, having called that subscriber in the usual way, if a simple calling-signal is used, or having had 25 the operator at central call him if a selective signal is used, the subscriber presses the button d^4 with his receiver off the hook. This operates the circuit-breaker e^3 , which breaks the bridge across the line from the talking-circuit e and by means of the switch h' establishes another bridge or circuit through the branch d and condenser d^3 across the line between the terminals a^2 b^2 . The condenser d^3 prevents the battery-current from flowing, 30 but will permit the alternating currents formed by the transmitters of the operator or the other subscriber to pass through, and thus enable the first subscriber to hear when the connection has been made. After the 35 proper connection has been established between the called subscriber and the calling subscriber on the same line the calling subscriber releases his button d^4 and the connection is established between the two subscribers. As soon as the called subscriber has 40 removed his telephone from the hook a new bridge will be established, which will immediately operate the relays f' in each of the other subscribers' stations and lock them out 45 except the two subscribers which have thus been connected.

It will be seen that by this construction an absolutely positive and automatic lock-out device is secured which can be attached to any 50 common-battery system. The relays f' and f^2 , with their circuit-breaking devices, are connected onto the line in the manner shown, but are normally inactive, the one because it is connected to the side of the line which is 55 grounded at central station and the other

because it is in an open grounded circuit, which will only be closed by removing the telephone from the hook.

The means provided for establishing connection between two subscribers on the same line is such that the current is prevented from flowing across the bridge until the second subscriber called has been connected, and hence prevents the operation of the lock-out device until the called subscriber has come 70 into the line, which being accomplished all the other subscribers will be immediately locked out.

Having thus described my invention, I 75 claim—

1. In a common-battery telephone system, a main line having a series of talking instruments or subscribers' stations adapted to be bridged across the line, a relay in a normally open grounded line, a switch operated by the 80 telephone-hook to close said grounded line through said relay, and a circuit-breaker operated by said relay to close the talking-circuit across the telephone-line, a second relay at each subscriber's station in a normally 85 grounded circuit from the opposite side of the line, and having a circuit-breaker in the main talking-circuit, said second relay being adapted to be operated whenever a bridge is 90 established across the main line, substantially 95 as specified.

2. In a common-battery party-line telephone system, a series of subscribers' stations, each having talking instruments adapted to be bridged across the line by a relay in a grounded circuit adapted to be closed by the main telephone switch or hook, a circuit-closer operated by said relay to bridge the talking instruments across the line, a second relay on a grounded circuit from the opposite 100 side of the line, and a circuit-breaker operated by the first relay to break the circuit through the second relay, substantially as 105 and for the purpose specified.

3. In a common-battery party-line telephone system, a normally open grounded connection from one side of said battery, a grounded connection at each subscriber's station from the opposite side of said battery, including a relay and the main telephone-switch, a bridge across the line at each subscriber's station including the talking instruments, and a circuit-closer operated by said relay, a second relay adapted to operate a switch in said talking-circuit, said second relay being in a grounded circuit on the same 115 side of the battery as the ground at central station, and means for breaking the circuit through said second relay when the first relay is operated, substantially as and for the purpose specified.

4. The combination with a central-energy party-line telephone system, having a battery grounded at one side, relays at each subscriber's station in grounded circuits extend- 120 125 130

ing from opposite sides of said line, one of said relays being normally closed to ground and the other relay being normally opened at a switch operated by the main telephone-hook, the operation of one of said relays being adapted to close the talking-circuit across the line, and the operation of the other relay being adapted to break the talking-circuit across the line, the closing-relay being also adapted to break the circuit from the relay in the same subscriber's station when the same is operated, substantially as and for the purpose specified.

5. In a central-energy party-line telephone system, a relay adapted to be thrown in circuit by the operation of the telephone-hook and to establish a connection across the line with the subscriber's telephone instruments,

means for breaking the connection in all the other subscribers' instruments whenever the current is thus permitted to flow from the battery across the line, and a shunt including a condenser and a circuit-breaker adapted to break the bridge including the talking instruments across the line and establish a connection through said talking instruments and the condenser, substantially as and for the purpose specified.

In testimony whereof I have hereunto set my hand this 17th day of October, A. D. 1905.
